US00D965150S

(12) **United States Design Patent** (10) **Patent No.:** **US D965,150 S**
(45) **Date of Patent:** **** Sep. 27, 2022**

(54) **PROSTHESIS ANCHOR**

(71) Applicant: **HOWMEDICA OSTEONICS CORP.**,
Mahwah, NJ (US)

(72) Inventors: **Robert Courtney**, Pierceton, IN (US);
Austin W. Mutchler, Warsaw, IN (US);
Jeffrey M. Ondrla, Warsaw, IN (US)

(73) Assignee: **HOWMEDICA OSTEONICS CORP.**,
Mahwah, NJ (US)

(**) Term: **15 Years**

(21) Appl. No.: **29/673,310**

(22) Filed: **Dec. 13, 2018**

(74) *Attorney, Agent, or Firm* — Duane Morris LLP

(57) **CLAIM**

The ornamental design for prosthesis anchor, as shown and described.

DESCRIPTION

FIG. 1 is a top perspective view of an embodiment;
FIG. 2 is a bottom perspective view of the embodiment of FIG. 1;
FIG. 3 is a front view of the embodiment of FIG. 1;
FIG. 4 is a back view of the embodiment of FIG. 1;
FIG. 5 is a left side view of the embodiment of FIG. 1;
FIG. 6 is a right side view of the embodiment of FIG. 1;
FIG. 7 is a top view of the embodiment of FIG. 1; and
FIG. 8 is a bottom view of the embodiment of FIG. 1.
FIG. 9 is a top perspective view of another embodiment;
FIG. 10 is a bottom perspective view of the embodiment of FIG. 9;
FIG. 11 is a front view of the embodiment of FIG. 9;
FIG. 12 is a back view of the embodiment of FIG. 9;
FIG. 13 is a left side view of the embodiment of FIG. 9;
FIG. 14 is a right side view of the embodiment of FIG. 9;
FIG. 15 is a top view of the embodiment of FIG. 9; and,
FIG. 16 is a bottom view of the embodiment of FIG. 9.
The broken lines are included for purposes of illustrating such portion of the prosthesis anchor and form no part of the claimed design.
